CLAIM

We claim the ornamental design for an optical communication module, as shown and described.

DESCRIPTION

FIG. 1 is a front left perspective view of an optical communication module showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side view thereof; and,

FIG. 7 is a left side view thereof.

The broken lines in the drawings depict portions of the optical communication module that form no part of the claimed design.
